US00D340402S

United States Patent [19]**Holt**[11] **Patent Number:** **Des. 340,402**[45] **Date of Patent:** **** Oct. 19, 1993**[54] **PICTURE HANGING APPARATUS**4,893,776 1/1990 Floyd .
4,993,168 2/1991 Acuna .
5,028,030 7/1991 Lewis ..... 248/493[76] **Inventor:** **G. Richard Holt, 100 Pin Oak Forest,
San Antonio, Tex. 78232**[**] **Term:** **14 Years****FOREIGN PATENT DOCUMENTS**

708874 7/1941 Fed. Rep. of Germany .

[21] **Appl. No.:** **874,763***Primary Examiner*—Wallace R. Burke[22] **Filed:** **Apr. 27, 1992***Assistant Examiner*—H. Baynham[52] **U.S. Cl.** ..... **D8/373***Attorney, Agent, or Firm*—Richard J. Smith[58] **Field of Search** **D8/373; 248/544, 493;
D6/300****CLAIM**The ornamental design for a picture hanging apparatus,
as shown and described.[56] **References Cited****DESCRIPTION****U.S. PATENT DOCUMENTS**

1,294,643 2/1919 Farb .
2,428,213 9/1947 Gloede .
3,406,460 10/1968 Colwell .
4,026,510 5/1977 Holmes 248/493
4,382,337 5/1983 Bendick .
4,443,949 4/1984 Newton .
4,559,690 12/1985 Asmus .
4,637,583 1/1987 Babitz .

FIG. 1 is a perspective view of a picture hanging apparatus showing my new design;

FIG. 2 is a top plan view thereof;

FIG. 3 is a right side view thereof;

FIG. 4 is a front elevational view thereof;

FIG. 5 is a rear elevational view thereof;

FIG. 6 is a right side view thereof; and,

FIG. 7 is a bottom plan view thereof.
